UNITED STATES PATENT OFFICE.

PAUL A. ROSE, OF CRANFORD, NEW JERSEY, ASSIGNOR TO OXWELD ACETYLENE COMPANY, OF CHICAGO, ILLINOIS, A CORPORATION OF WEST VIRGINIA.

GAS-LIGHTING FIXTURE.

1,283,313.

Specification of Letters Patent. Patented Oct. 29, 1918.

Application filed March 17, 1917. Serial No. 155,479.

To all whom it may concern:

Be it known that I, PAUL A. Rose, a citizen of the United States, residing at Cranford, county of Union, and State of New Jersey, have invented certain new and useful Improvements in Gas-Lighting Fixtures, of which the following is a full, clear, and exact description.

This invention relates to certain new and useful improvements in shade holders for gas burners and is particularly adapted for use with acetylene burners where it is desired to use an inverted globe. In the burning of acetylene it has been found impracticable to use the well known type of inverted burner since the heat of combustion so heats up the conducting tube that the acetylene disassociates into various undesirable compounds.

In the present invention I provide a holder adapted for use in connection with the well known upright burner, which holder is adapted to receive and support an inverted globe. The parts are so arranged that the holder can be placed in position without disassembling or detaching the burner tube and when so assembled the burner tube is disposed to one side of the burner whereby the heat of combustion does not disassociate the acetylene in the tube.

Further objects of my invention reside in the provision of a device which is inexpensive to manufacture and in which the assembly of the parts is simplified.

In the drawings:—

Figure 1 is a view in cross section showing the shade or globe holder in position on the burner tube.

Fig. 2 is a plan view, omitting the globe and burner.

Fig. 3 is a section showing modified method of attaching the bracket supporting boss to the burner tube.

Figs. 4 and 5 are sections on lines 4—4 and 5—5 respectively, showing two methods of fastening the bracket or spider to the shade holder.

In more detail, 10 is the burner tube. This tube, which is threaded at its upper end for connection in the usual way with a source of gas, not shown, extends downward and is curved at its lower end to space the burner 10^a, screwed upon nipple 11, laterally away from the tube. At a suitable height above the lower end of the tube

there is a ring 12 having a radial flange 13, the ring and its flange being in one piece, punched from sheet metal and secured to the burner tube by soldering, or by crimping as indicated at 14 in Fig. 3.

The shade or globe holder 15 is of sheet metal and carries the usual globe-holding set screws 16. To support the shade holder in place I provide a bracket or spider 17 which comprises a piece of bent wire or other stock bent to form a Y-shaped portion or bight 18, the end portions 19, 20, flaring as shown. The latter, and the outermost end of the Y-portion are attached to the shade holder either by screws 21, as in Fig. 5, or by extruding a part of the metal of the bracket and riveting this portion over as shown at 22 in Fig. 4.

It will be observed that the crotch or Y-shaped portion of the bracket is eccentric to the annular globe-holder 15. When it is desired to put the holder and globe in place upon the burner tube the holder is passed up over the end of the burner tube, the burner being already in place. As shown in Fig. 2 there is ample room to pass the burner tube and burner between the bracket arms 19, 20. The holder is then displaced laterally until the pipe 10 abuts against the crotch in the Y-portion of the bracket, the latter resting upon flange 13. Screws 23 are then passed through holes in the bracket and screwed into tapped holes in the said flange 13 of ring 12. The globe (indicated in dotted lines at 24) is then inserted and secured in the ring or holder 15, and the burner is ready for use. To remove the globe and globe-holder from the burner tube the operations just described are reversed.

While not essential it is desirable to have the crotch or Y-portion of the bracket spaced far enough laterally from the center of the globe-holder 15 to bring the center of the latter substantially into vertical alignment with the burner, as in Fig. 1. The angle between the arms 19, 20, is rather wide, so that neither will be directly over the burner. Preferably they are spaced as far as possible from the plane of the burner and burner tube, to minimize heating of the arms and consequent conduction of heat to the burner tube.

It is to be understood that the invention is not limited to the specific construction herein specifically described but can be em-

bodied in other forms without departure from its spirit.

I claim:

1. The combination with a depending 5 burner tube having a laterally displaced burner at its lower end, of a globe-holder above the burner, and a bracket having a crotch embracing and supported by the burner tube and having a plurality of arms 10 attached to the globe-holder to support the same, the crotch being eccentric to the globe-holder whereby the center of the latter is held in substantially vertical alinement with the burner.
- 15 2. A globe-holder adapted for attachment to a depending burner tube having a laterally displaced burner, comprising a globe-holding frame; a bracket within the frame and having branch portions secured there- 20 to, with a crotch portion adapted to embrace the burner tube, the crotch portion being eccentric to the said frame, to permit passing of the burner tube and attachments between the frame and the bracket; and 25 means for securing the bracket to the tube when the latter is in the aforesaid crotch portion.
3. A lighting fixture comprising a depending burner tube having an offset lower 30 end carrying a burner, a bracket-supporting

member on the said tube, a bracket independent of the burner tube and adapted for attachment to said member, a globe-holder attached to the bracket, said bracket being constructed to permit passing of the burner 35 and burner tube between the globe-holder and the bracket and to support said holder centrally over the burner, and means for attaching said bracket to said member.

4. The combination with a depending 40 burner tube having a laterally displaced burner at its lower end, of a globe holder above the burner, and a bracket having a crotch embracing and supported by the burner tube, said bracket having flattened 45 portions to receive screws for securing said bracket to the tube when the latter is in the aforesaid crotch portion.

5. A globe holder adapted for attachment to a depending burner tube having a later- 50 ally displaced burner, comprising a globe holding frame, a bracket within the frame and formed of one piece of wire bent to Y-shape with a widened portion in the stem of the Y to accommodate the burner tube, and means for securing the bracket to the tube when the latter is in the aforesaid position.

In testimony whereof I affix my signature.

PAUL A. ROSE.
